WILHELM LENK, OF REMSCHEID-LENNEP, GERMANY, ASSIGNOR TO BARMER MACHINENFABRIK AKTIENGESELLSCHAFT, OF REMSCHEID-LENNEP, GERMANY

THREAD BRAKE FOR TWISTING SPINDLES

Application filed January 5, 1931, Serial No. 506,795, and in Germany January 23, 1930.

This invention relates to a thread brake, which is employed on twisting spindles, in which during every spindle rotation, two or more twists are imparted to the thread. 5 Such thread brakes are in themselves known and are arranged always in front of the point of admission of the thread into the hollow spindle in order to thus impart to the thread the tension necessary for the uniform twisting. 10 For this purpose the thread has hitherto been wound several times around a suitable device and then passed through the spindle. This is however open to the objection, that the thread, owing to the different occurring tensions, can easily pull tight 15 on the running off bobbin so that thread breakage often occurs. Moreover, the threading of the thread into the hollow spindle at the beginning of the twisting is rendered difficult, as the thread is not smoothly conducted through the spindle by the running off bobbin.

These disadvantages are overcome by the invention. The novelty consists in that the 25 thread brake consists of an outer sleeve, the admission and discharge apertures of which are closed in the interior of the sleeve by spring controlled sleeves inserted one in the other telescope like. The admission and 30 discharge apertures terminate in the interior as conical enlargements bearing against the sleeves. The sleeves are closed each on the outer end by semispherical heads and pressed apart by a spiral spring arranged in the 35 sleeves. This construction of the thread brake enables the thread to be conducted through smoothly without entangling and to be put under tension merely at its admission and discharge on the upper and lower conical 40 surfaces. The telescoped sleeves can yield in longitudinal or in lateral direction owing to the conical bearing faces, so that there is no possibility of the thread pulling tight. Moreover, owing to this arrangement, an easy 45 threading of the thread is possible at the beginning of the twisting, as the threading needle can be passed through the tensioning device without hindrance, since the spring controlled sleeves can yield towards all sides. 50 However the sleeves, owing to their conical

bearing, always return into their initial position for closing the admission and discharge apertures of the thread brake. Pulling tight of the thread within the thread brake can also not occur during the pulling off of the 55 thread from the running off bobbin and the circular motion caused thereby, as, owing to the smooth internal construction and the easy yieldability of the brake, the thread can move freely without any possibility of 60 entangling.

An embodiment of the invention is illustrated by way of example in the accompanying drawings in which:

Fig. 1 shows the thread brake in elevation. 65
Fig. 2 is a longitudinal section of the brake.
Fig. 3 is a cross section on line III—III of Fig. 1.

The outer sleeve 1 of the thread brake is arranged for example in the bobbin holder 70 2 in front of the hollow spindle. The sleeve 1 has an aperture 3 at the top and an aperture 4 at the bottom, which apertures have each a conical enlargement 5 and 6 respectively on the inner ends. Telescopic sleeves 7 and 8 bear against these conical surfaces for the purpose of closing the apertures 3 and 4. These sleeves 7 and 8 are semispherical at the top and bottom ends and forced apart by an inner spring 9. The thread 10 therefore is put under tension at the admission and discharge apertures 3 and 4, the sleeves 7 and 8, owing to their conical bearing surfaces 5 and 6 and owing to their construction, being able to yield and shift towards all 75 sides. Evidently the thread brake according to the invention can also be used as spinning and twisting tube. 80

I claim:-

1. A thread brake, comprising in combination with a twister spindle an outer sleeve having an admission and a discharge aperture, two inner telescopic sleeves in said outer sleeve adapted to close said apertures, and a spring in said telescopic sleeves 95 adapted to force apart said inner telescopic sleeves.

2. A thread brake as specified in claim 1, in which the admission and discharge apertures are conically widened at the inner end 100

to form bearing surfaces for said inner telescopic sleeves.

3. A thread brake comprising in combination an outer sleeve having an admission and a discharge aperture conically enlarged at the inner ends, inner telescopic sleeves in said outer sleeve, a semispherical head on the outer end of each of said inner sleeves adapted to bear against said conical widened portions of and to close said apertures in said outer sleeve, and a spiral spring in said inner sleeves adapted to press said heads against the conical portions of said outer sleeve.

15 In testimony whereof I affix my signature.
WILHELM LENK.
